UNITED STATES PATENT OFFICE.

DIEDRICH LIENHOP, OF ST. LOUIS, MISSOURI.

PARLOR-FOUNTAIN.

SPECIFICATION forming part of Letters Patent No. 307,966, dated November 11, 1884.

Application filed February 16, 1884. (No model.)

To all whom it may concern:

Be it known that I, DIEDRICH LIENHOP, of the city of St. Louis and State of Missouri, have invented a certain new and useful Improvement in Parlor-Fountains, of which the following is a full, clear, and exact description, reference being had to the accompanying drawings, forming part of this specification.

Figure 1 is an elevation of the fountain. Fig. 2 is an axial section of the fountain, basin, and stand, the pump-works being shown in elevation. Fig. 3 is an enlarged horizontal section at 3 3, looking down. Fig. 4 is an enlarged vertical section of the pump at 4 4. Fig. 5 is a perspective view of the sprinkling-nozzle and coupling.

A are the legs supporting a frame, B.

C C are shelves supported upon the frame B, and intended for a support for flower-pots D.

E is the water-basin into which the water from the fountain descends.

F is a drain-pipe from the basin E, said pipe supplying water to the induction-chamber G of the pump.

H H' are check-valves working in the induction-ports I, between the chamber G and the water-chambers J, that are in communication with the induction-ports K of the pump-cylinder L.

M is the pump-piston, and N the piston-rod, which latter works through a stuffing-box, O.

P is a stud upon the piston-rod, that enters the groove r of an oblique cam, R, upon a shaft, S. The shaft S is actuated by weight T through a multiplying system of cog-gear, U. The weights are supported upon hooks v on

cords V and V', which are coiled in opposite directions on the cord-shaft or drum W, so that the uncoiling of the cord V will coil up 40 the cord V' upon the drum, and vice versa. Thus when one cord has been uncoiled from the drum the weight is transferred to the other cord, and so on. I prefer to place a friction-roller on the stud P, to lessen the friction and 45 wear. The eduction-valves are shown at X, their ports opening into the eduction-chamber Y, from which the jet-pipe Z extends upward through the bottom of the basin E.

Z' is the nozzle throwing a fine jet or jets. 50

a is a coupling-cap that may be fitted upon the nozzle Z'. The coupling-cap carries a hose-section, b, at whose free end is a rose-jet, c, by which water may be sprinkled upon the plants in the pots D upon the shelves. 55

d is an air-chamber above the eduction-chamber Y, to insure regularity of the water-jet by equalizing the pressure.

I claim as my invention—

1. The combination of weight T, drum W, 60 with cord V, cog-gear train U, cam-shaft and cam S R, a pump operated by the cam, and the fountain-pipe Z, and return-pipe F, substantially as set forth.

2. The combination, with the piston-rod N 65 and stud P, of the oblique cam R, gearing U, and driving-drum carrying cords V V', wound in opposite directions upon the drum, for the purpose set forth.

DIEDRICH LIENHOP.

In presence of—

GEO. H. KNIGHT,
J. WAHLE.
